UNITED STATES PATENT OFFICE.

MARK THOMAS DENNE, OF RUSHDEN, ENGLAND.

ROTARY CUTTER FOR SKIVING OR TRIMMING MACHINES.

1,230,875.

Specification of Letters Patent. Patented June 26, 1917.

Application filed January 17, 1914. Serial No. 812,819.

To all whom it may concern:

Be it known that I, MARK THOMAS DENNE, a subject of the King of Great Britain and Ireland, residing at Rushden, Northamptonshire, England, have invented new and useful Improvements in and Relating to Rotary Cutters for Skiving or Trimming Machines, of which the following is a specification.

This invention has reference to improvements in and relating to rotary cutters for skiving or trimming machines, and it consists in the combination of a cutter or knife made of thin ribbon of steel and an expandable drum to carry said knife so that the knife or cutter may be easily applied or removed by merely contracting the drum whereas when the cutter has been adjusted in position and the drum expanded said cutter will be firmly held so as to be compelled to rotate with the drum and whereby the knife or cutter although made of thin ribbon steel will yet be maintained rigid and its lateral deflection prevented.

A constructional form of my invention is illustrated in the accompanying drawing, Figure 1 being a front view and Fig. 2 a side elevational view partly in section.

In said drawing A indicates a bearing with which a suitable frame—not shown—is formed or provided, and which supports a spindle or shaft B to which rotary motion may be imparted in any usual suitable manner.

On one end of the spindle I mount a *quasi* expansion clutch comprising two members C and D. The member D is secured to the shaft in any suitable manner—for example by being screwed thereon to about against a collar d —(which latter in conjunction with, say, another collar may serve to prevent axial movement of the shaft B) so as to be rotatable with the shaft and the other member, C, is slidable on the shaft so that it may be pressed or forced closer to or allowed to recede from the member D.

The member D is formed with slits or slots S of suitable dimensions around its periphery and it has a cylindrical outer bearing surface d' . The inner surface of the peripheral part is made conical and the outer peripheral part of the member C is made correspondingly conical so that when the member C is pressed or forced against the member D the slotted portion will ex-

pand and the effective diameter of the member D will be thereby increased.

The knife or cutter E is made of thin ribbon steel the ends of which may be brazed or welded together or it may be made by rolling on the principle of tire rolling. It is made cylindrical and snugly fits on the cylindrical bearing surface d' when the member D is at its smaller diameter and said member is preferably formed or provided with a shoulder d^2 against which the inner edge of the knife or cutter abuts.

The member C may be pressed or forced against D by means of a nut F which is screwed on the end of the shaft B and which nut may be rotated by a spanner or other suitable means or it may be made with apertures f in which a key fits.

The outer edge of the knife is sharpened—preferably after it has been adjusted and fixed on the drum—and if desired I may provide a sharpening means—for example an emery wheel—so that said cutter may be sharpened as may be necessary from time to time.

If desired the knife E may be made to project on both sides of the drum and have a cutting edge on both sides thereof.

The cutter or knife although made of thin steel is quite rigid when the drum has been expanded and is therefore much more practical for use in skiving, inseam trimming and the like than is an endless band saw or cutter in which the endless band is passed over two drums or pulleys and its lateral displacement to some extent prevented by means of guide rollers or the like.

Further the cost of my thin cylindrical cutter is much less than is the cost of the ordinary dished cutters heretofore generally in use in skiving and inseam trimming machines so that the renewals in the cutters will very soon make my machine less expensive than those in use notwithstanding some slight greater first cost.

In addition to the frictional engagement of the expanded drum with the cutter or knife to prevent relative movement I may provide the drum with pins or the like passing through or engageing with the knife whereby such relative movement will be absolutely prevented.

What I claim as my invention and desire to secure by Letters Patent is:—

1. A knife for skiving or trimming ma-

chines, comprising in combination a holder in the form of a drum capable of being freely expanded radially, a flexible cylindrical knife blade mounted on the periphery or outer surface of the said drum with its cutting edge projecting laterally beyond the drum, and means for uniformly and radially expanding every point on the outer surface of the drum into contact with the inner surface of the knife blade, so that the latter is conformed to the periphery or outer surface of the drum.

2. A knife for skiving or trimming machines, comprising in combination an expandable holder in the form of a drum having a cylindrical outer surface and an inner conical surface, a flexible cylindrical knife

blade mounted on the periphery of the said drum with its cutting edge projecting laterally beyond the drum, and a member having a conical surface adapted to be forced against said inner conical surface of the drum, said member being slidably and concentrically mounted within the drum and adapted to expand the drum against the knife blade when forced against said inner conical surface of the drum.

In testimony whereof I have signed my name to this specification in the presence of two subscribing witnesses.

MARK THOMAS DENNE.
